ABSTRACT OF THE DISCLOSURE

A vacuum operated pump having an axially aligned pair of pistons of different diameters operating in respective low and high pressure cylinders where a piston operating in the larger cylinder compresses air and transmits said compressed air into the smaller high pressure cylinder where the smaller piston produces further and higher compression for transmission to work apparatus or storage means. The invention further includes a control rod operating in conjunction with the vacuum diaphragm and mounted axially in respect of said diaphragm and said pistons and extending externally of the apparatus housing to operate an alternating vacuum control mechanism.

BACKGROUND OF THE INVENTION**Field of the invention**

This invention relates to a novel vacuum operated pump or compressor for use in connection with motor vehicle and stationary engines or other vacuum sources for establishing and maintaining fluid pressure in systems such as shock absorbers, tire inflating devices, load leveling devices, air brakes, air horns, spraying equipment, and other systems requiring compressed air and other fluids under pressure.

Description of the prior art

The present invention constitutes an improvement over prior art devices such as disclosed in the following U.S. Pats. Nos. 2,136,475, 2,630,102, 3,148,825, 3,151,804, 3,151,805, 3,253,775 and 3,339,830. The prior art devices as exemplified by said patents manifest various functional deficiencies inherent in their respective structures. One serious drawback is involved in the mounting of a control element laterally of the reciprocating piston elements for operating an alternating vacuum control mechanism thereby subjecting the working parts of the apparatus to off center stresses that derogates from the desired balance that reciprocating parts should exhibit in performing their pumping functions.

In some prior art devices, the lateral control element must, of necessity, extend through a piston wall or through a wall of a vacuum chamber thereby involving leakage of air which considerably reduces the efficiency of the pump. In efforts to counteract such unbalancing forces, prior art devices were constrained to incorporate extremely close tolerances between working parts which are deleterious to the operating function and structure and involved complex means for reducing leakage of air either from the piston cylinders or from the vacuum chambers.

Also, in prior double-acting vacuum operated pumps, the pistons have been located on opposite sides of the vacuum operated diaphragm and have been located within respective vacuum chambers on opposite sides of the diaphragm. This reduces the effective area of the diaphragm by the area of the piston by as much as approximately 15% on the low pressure side, and approximately 10% on the high pressure side in one such prior art device. Likewise, the cubic content of each vacuum chamber is

increased and thus requires more volume of vacuum per stroke as well as higher vacuum to offset loss of diaphragm effective area for a given output pressure. Since the movable pistons are operative within the respective vacuum chambers and are movable in respect thereof while negative pressures are being induced therein, it is manifest that considerable loss in pumping efficiency has been experienced in such prior art devices.

Summary of the invention

10 In order to overcome the disadvantages and deficiencies of prior art apparatus, the present invention comprises a novel arrangement of mounting two pistons longitudinally in respect of each other on the same operating axis in separate piston cylinders, both of said cylinders being aligned axially on one side only of the vacuum operated diaphragm of the pump. The two cylinders are effectively isolated from the vacuum chambers within which the diaphragm is operative whereby vacuum losses 15 within said vacuum chambers are practically eliminated. One piston is operative in a large low pressure cylinder for compressing air during one half of the operating cycle of the pump and transmitting said compressed air to the second smaller high pressure cylinder where the second 20 piston is operative on the second half operating cycle to compress the air to a higher pressure for transmission to work or storage apparatus.

Furthermore, an additional feature of the invention is the mounting of a control element axially of the vacuum 25 diaphragm and axially of the two pistons, said control element extending externally of the apparatus housing and operating an alternating vacuum control mechanism.

By mounting the control element axially of the operating parts in the interior of the apparatus, no off-center 30 stresses are applied to said operating parts whereby pumping efficiency is not reduced.

The axial location of the control element in respect of the operating parts and in respect of the apparatus housing 35 obviates the necessity for complex and expensive sealing means to preserve the negative pressure conditions within the vacuum section of the apparatus and permits the use of comparatively wide tolerances without any reduction in pumping efficiency.

A further feature of the invention is the provision of 40 a seal in the partition between the vacuum chamber and pumping chamber of the apparatus, said seal being effective during both rectilinear motions of a rod moving through an O-ring. The O-ring provides a vacuum seal for the vacuum chamber when negative pressure is being 45 induced therein adjacent said partition, notwithstanding the opposing frictional force of a rod moving through said O-ring during that time. Said O-ring also performs its sealing function when the piston assembly mounted on 50 said rod moves toward said partition and produces increased air pressure for urging said O-ring into its sealing 55 position.

These and other novel features and advantages of the 60 present invention will be described and defined in the following specification and claims.

BRIEF DESCRIPTION OF THE DRAWINGS

FIG. 1A is a vertical one-half central section of the 65 pump of the present invention showing the movable pumping elements located at or near the end of their their respective downward strokes, some parts being shown in elevation and some parts in dotted outline;

FIG. 1B is comparable to FIG. 1A and shows the movable pumping elements located at or near the end of their respective upward strokes;

FIG. 1C is an enlarged fragmentary section view of 70 a portion of the upper piston shown in FIG. 1A after said piston has started its upward stroke;

FIG. 1D is an enlarged fragmentary section view of a portion of the upper piston shown in FIG. 1B after said piston has started its downward stroke;

FIG. 1E is an enlarged fragmentary section view of a portion of the lower piston shown in FIG. 1A after said piston has started its upward stroke;

FIG. 1F is an enlarged fragmentary section view of a portion of the lower piston shown in FIG. 1B after said piston has started its downward stroke;

FIG. 2 is a top fragmentary view of the device shown in FIGS. 1A and 1B, some parts being shown in section, some parts in dotted outline, and some parts partly broken away, and particularly illustrating the portion of the vacuum control valve mechanism and its operating linkages for alternating the vacuum conditions in the interior of the pump;

FIG. 3 is a fragmentary view similar to FIG. 2 showing the valve mechanism in an alternate position;

FIG. 4 is similar to FIG. 3 with further parts being broken away and other parts being shown;

FIG. 5 is an enlarged fragmentary perspective view of the mechanism shown in FIGS. 2, 3 and 4;

FIG. 6 is a view taken on line 6—6 of FIG. 5;

FIG. 7 is an enlarged perspective view of the top of the valve element;

FIG. 8 is a perspective view of the bottom of the valve element shown in FIG. 7;

FIG. 9 is a fragmentary central section view of the apparatus shown in FIGS. 1A and 1B showing an alternative embodiment of the apparatus in one position;

FIG. 10 is similar to FIG. 9 showing parts of the apparatus in another position;

FIG. 11 is similar to FIGS. 3 and 4 with further parts omitted and showing the connection of a valve detent spring; and

FIG. 12 is a perspective view of a valve detent spring.

DESCRIPTION OF THE PREFERRED EMBODIMENTS

FIGS. 1A and 1B of the drawing each show respective complementary halves of the apparatus herein in vertical section wherein like numbers refer to similar parts which are shown in different operational locations in said figures. Except for the alternating vacuum control and other parts specified herein, each part of the device may be assumed to be substantially circular in horizontal cross-section.

Referring now to the drawings in detail, the body of the device comprises a pair of bell sections 11 and 12, each having annular mating flanges 13 and 14, respectively, which are secured together by means of a plurality of spaced apart screws 16 in circular array. Clamped fast between flanges 13 and 14 is the peripheral edge portion of a flexible diaphragm 17 which is movable within the space enclosed by bell sections 11 and 12 and which divides and separates said space into two chambers 18 and 19 which vary inversely in volume according as said diaphragm moves in one vertical direction or the other. Bell section 11 has a top end wall 21 which has a central axial aperture 22 which accommodates a reciprocating control rod 23 therein. End wall 21 has a raised collar 24 surrounding rod 23 and encloses a widened axial aperture in which is positioned O-ring 26 which is held captive by a spider retaining ring 27 secured frictionally within collar 24. O-ring 26 serves as a one-way vacuum seal for chamber 18.

Bell section 12 has an end wall 28 that serves as a partition between vacuum chamber 19 and the piston assembly of the apparatus. Partition 28 has a central axial aperture 34 through which tubular shaft or piston rod section 36 moves reciprocably, there being a slight clearance between said rod and said aperture. Mounted on the upper and lower surfaces of the central portion of diaphragm 17 are respective circular clamp plates 37 and 38, said clamp plates being secured together by means of

threaded nut 43 mating with threaded rod 36. The lower portion of rod 23 extends freely longitudinally with wide clearance through axial aperture 44 in nut 43 and through axial aperture 46 in rod 36. The vertical reciprocating motion of diaphragm 17 imparts a corresponding reciprocating motion to rod section 36.

Integrally formed on the lower surface of partition 28 of bell element 12 is a collar 47 coaxially aligned with aperture 34. Formed within collar 47 is an annular recess 48 which accommodates a somewhat loosely fitting O-ring 49 which serves as a seal between partition 28 and rod section 36. O-ring 49 is held captive within recess 48 by means of a spider retaining ring 51 whose inside diameter provides a wide clearance for rod 36, thereby permitting free flow of air therethrough.

Formed integrally with and arrayed in a circle near the periphery of wall 28 of bell section 12 are a number of spaced apart bosses 56 extending downwardly thereof, said bosses each having a longitudinal threaded recess 57. A compound piston pressure chamber housing, generally designated 58, is formed of two integrally formed coaxial sections, namely, a low pressure cylinder 59 and a high pressure cylinder 61 whose diameter is smaller than that of cylinder 59. Cylinder 59 has a plurality of integrally formed spaced apart outwardly extending bosses 62, each having an aperture through which a bolt 63 extends to engage respective threaded recesses 57 in bosses 56. The upper circular end of cylinder 59 has an annular recess accommodating resilient O-ring 64 which is caused to bear against the bottom surface of wall 28 when bolts 63 are tightened thereby producing a leak-tight seal between said cylinder and said wall.

Threadedly or otherwise secured to rod section 36 is a cylindrical piston 66 which is moved reciprocably by said rod section within low pressure chamber 67 bounded by cylinder 59. The upper perimeter portion of piston 66 has an annular recess 68 which accommodates a resilient O-ring 69. The top peripheral area of piston 66 has a plurality of spaced apart apertures 72 in circular array which communicate with recess 68 to provide for bypass of air during the downward suction stroke of piston 66 (FIG. 1A). During the upward pressure stroke of piston 66, O-ring 69 is urged against flange 73 of rim 68 (FIG. 1C) so, that during its upward stroke, piston 66 compresses the air into the upper portion of chamber 67.

Piston 66 is provided with a plurality of spaced apart laterally extending apertures 74 which provide for bypass of air from the bottom of chamber 67 through apertures 72 during the downward suction stroke of piston 66 when O-ring 69 is urged upwardly against flange 75 of said piston. Mounted in a suitable annular recess 76 in the lower periphery of piston 66 is a lubricated or unlubricated felt or plastic ring 77 which serves to ensure the alignment of piston 66 and to prevent scoring between parts. Recess 76 communicates with an optional auxiliary annular recess 78 which serves as an expansion chamber for ring 77 and to contain a lubricant, if desired or necessary, for said ring.

Threadedly or otherwise secured to the lower end portion of rod section 36 is a second tubular rod section 81 which has an axial aperture 82 which accommodates a longitudinally movable valve pin 83. Mounted fast on the lower end of valve pin 83 is a valve 84 made of a suitable resilient material such as rubber, or the like, and which cooperates with a recessed valve seat 86 formed in the lower end of second piston rod 81. Valve 84 is normally urged against valve seat 86 by the action of spring 87, the lower end of which bears against an interior annular shoulder formed in rod 81, the upper end of which bears against a collar 88 mounted fast at or near the upper end of valve pin 83.

Threadedly secured or otherwise mounted fast at the lower end portion of rod 81 is a high pressure piston 91 which moves reciprocably within high pressure chamber 92 of cylinder 61. Piston 91 has a peripheral annular

recess 93 which accommodates an O-ring 94 made of suitable resilient material.

In some embodiments, the inner portion of recess 93 comprises a generally V-shaped annulus formed by walls 96 and 97 arrayed at an included angle on the order of about 75° to 90°. Walls 96 and 97 terminate in walls 98 and 99, each of which are arrayed directly perpendicularly to the axis of the pump or are inclined, respectively, upwardly and downwardly from the perpendicular by an angle of from 0° to about 10°. O-ring 94 is nested in recess 93 with only a minimum amount of pressure against walls 96 and 97 and the interior wall of chamber 92 so that there is a minimum of deformation or peripheral squeeze of said O-ring when piston 91 is at rest.

By arranging for the recess 93 to have the special configuration formed by walls 96, 97, 98 and 99, there is ample space around O-ring 94 to permit its normal expansion due to heat created by the compression of air in chamber 92. In FIGS. 1A and 1B, O-ring 94 is shown in a neutral position at the respective ends of the downward and upward strokes of piston 91. The operating action of O-ring 94 will be explained hereinafter as particularly shown in FIGS. 1E and 1F.

Mounted in an annular recess 100 in the perimeter of piston 91 is a lubricated or unlubricated felt or plastic ring 101 which ensures the longitudinal alignment of piston 91 as well as prevents scoring between parts. Recess 100 communicates with an optional auxiliary annular recess 102 which serves as an expansion chamber for ring 101 and to contain a lubricant, if desired or necessary, for said ring.

Formed integrally between cylinders 59 and 61 is an annular shoulder 103 through which is bored a plurality of spaced apart ports 104 which provides for communication of atmospheric air with chamber 92 of cylinder 61 above piston 91 and with chamber 67 below piston 66. Integrally formed at the lower end of cylinder 59 is a downwardly extending flange 105 which forms an annular compartment with cylinder 61 to accommodate a filter ring 106 which is retained in place by a perforated ring 107 secured between flange 105 and the exterior surface of cylinder 61. Filter 107 serves to prevent contamination of atmospheric air introduced into pumping chambers 67 and 92 by dust or other foreign particles and materials.

Located centrally in end wall 108 of cylinder 61 is an outlet port 109 which communicates with a valve housing 111 formed integrally with and extending downwardly from said end wall. Positioned in the interior of housing 111 is a check valve 112 made of a suitable resilient material or the like, that is normally urged against valve seat 113 by one end of valve spring 114, the other end of which bears against tubular plug 116 threadedly inserted into the end of valve housing 111. Plug 116 has an integrally formed nut 117 by which said plug is threadedly removed and inserted. Integrally formed with nut 117 is a tubular ridged extension 118 to which suitable flexible connecting tubing is attached for transmitting air under pressure from cylinder 61.

A short distance above the top of piston 66, piston rod section 36 has a lateral port 121 which permits communication between that portion of low pressure chamber 67 above piston 66 and longitudinal aperture 82 in piston rod section 81 whereby during the upward stroke of piston 66 valve 84 is caused to become spaced apart from its valve seat (FIG. 1B) against the action of spring 87 so that air being compressed by the upward stroke of piston 66 is caused to enter into chamber 92 during the upward movement of piston 91. Thereafter, the downward motion of piston 91 causes the further compression of the air in chamber 92 and the expulsion of said air under pressure past valve 112 during which time valve 84 is firmly urged against valve seat 86 to prevent escape of air upwardly into aperture 82.

Mounted at the lower end portion of control rod 23 is a ring 122. Control rod 23 moves longitudinally in

respect of nut 43 and piston section 36. Upward motion is imparted to control rod 23 by interior annular bottom 123 of rod section 36 against the lower end of control rod 23 and the lower surface of ring 122, while downward motion is imparted to said control rod by the lower end of nut 43 bearing against the top surface of ring 122. It is evident that the longitudinal motion span of control rod 23 is shorter than the motion span of piston section 36 since piston section 36 performs a work function throughout both its complete upward and downward strokes whereas control rod 23 is required only to perform a short work stroke to operate a flip-flop or alternating mechanism described hereinafter for controlling the vacuum conditions in chambers 18 and 19 of the apparatus.

Aperture 44 provides a wide clearance to compensate for any possible misalignment of control rod 23. Also, the diameter of aperture 46 is large enough to provide a wide clearance for ring 122 for the same purpose.

Integrally formed with or otherwise mounted on one side of bell section 11 is a valve housing 131 which has an integrally formed, outwardly extending coupling tube 132, to which suitable, flexible hose may be attached for connection to the manifold of an automotive engine or the like which produces negative pressure. Tube 132 communicates with port 133 formed in the top surface 134 of housing 131. Port 133 is flanked on both sides by respective ports 136 and 137. Port 136 communicates by way of channel 138 and through flanges 13 and 14 with chamber 19 in bell section 12, while port 137 communicates by way of channel 139 in housing 131 with chamber 18 in bell section 11. Other suitable means may be devised for connecting ports 136 and 137 with respective chambers 18 and 19.

Mounted pivotally around pin 141 on the top surface 134 of housing 131 is valve element 142, as shown in FIGS. 2-8, the bottom surface of said element having an arcuate channel 143 as shown particularly in FIGS. 6 and 8. Recess 143 cooperates with ports 133, 136 and 137, in such manner as to establish communication between central vacuum port 133 and either one only of ports 136 and 137 according as said valve element is moved pivotally into either of two opposite directions as shown in FIGS. 2 and 3. When valve element 142 is pivoted clockwise as shown in FIG. 3, vacuum port 133 communicates through channel 143 with port 136 whereby a negative pressure is induced in chamber 19 of bell section 12 thereby producing downward movement of diaphragm 17 along with the downward movement of all of the other piston rod and piston elements connected thereto, see FIG. 1A. When valve element 142 is pivoted counterclockwise into the position shown in FIG. 3, vacuum port 133 communicates through valve channel 143 with port 137 whereby negative pressure is induced in chamber 18 in bell section 11, thereby producing the upward movement of diaphragm 17 as well as the upward movement of the piston rods and pistons connected thereto as shown in FIG. 1B.

A pair of spaced apart abutments 146 and 147 are secured by suitable pins in the top wall 134 of housing 131 and they serve to limit the respective clockwise and counterclockwise movements of valve element 142. Abutments 146 and 147 may be made of a suitable resilient material such as rubber or the like to absorb the impact of element 142.

Pivotal motion in clockwise and counterclockwise directions is imparted to valve element 142 by means of actuator pin 148 extending into and moving within arcuate recess 149 and abutting against the end walls of said recess in the top surface of valve element 142, see FIGS. 2-5 and 7. Pin 148 is mounted fast in the bottom of a valve actuator 151 pivotally mounted around pin 141. After valve element 142 has been caused to move pivotally in either clockwise or counterclockwise directions, said valve element is, during the intermittent time between

movements, retained against either one of abutment 146 and 147 by means of a semi-circular detent spring 152, one end of which is attached to tail projection 153 on valve element 142, the other end of which is connected to post 154 mounted on the top of bell section 11. Spring 152 offers no appreciable resistance, however, to the oscillating movement of valve 142.

The hub of valve actuator 151 has a circular projection 155 extending downwardly to the top surface 134 of housing 131 and the pivot aperture of valve 142 surrounds said projection with a sliding fit and is movable pivotally relative thereto, see FIG. 6.

Valve actuator 151 is also maintained intermittently between clockwise and counterclockwise motions by means of a link 156 having a forked end recess 157, the inner end of which is always urged against pin 158 mounted off-center on actuator 151. An elongated slot 159 at the other end of link 156 is engaged by and moves laterally relative to a post 161 mounted in the top wall 21 of bell section 11. A coil spring 162 surrounding link 156, one end of which bears against post 161, the other end of which bears against a shoulder 163 in said link, serves to maintain valve actuator 151 in a stationary position intermittently between clockwise and counterclockwise motions of said actuator. Slot 159 serves to permit the free pivoting action of link 156 relative to pins 158 and 161 while continuing to be engaged thereby.

Clockwise and counterclockwise motion is imparted to valve actuator 151 by means of a link bar 166 near one end of which is an elongated slot 167 which is engaged by a pin 168 mounted off-center on the top of said actuator. Slot 167 permits actuator 151 to move to opposite rest positions as determined by link 156 and spring 162, after link bar 166 has caused said actuator to move past the dead center position between its successive clockwise- and counterclockwise movements. Spring 162 and link 156 work in conjunction with link bar 166 to produce the desired snap action for valve 142.

The other end of link bar 166 is connected pivotally to the lower forked portion of pivot bar 171 by means of pivot pin 172. The upper portion of pivot bar 171 is mounted pivotally by means of pin 173 upon a post 174 mounted fast in the top wall 21 of bell section 11. Pin 173 extends through washers 176 on opposite sides of post 174 and through pivot block 177. Both pivot bar 171 and pivot block 177 are mounted fast upon pin 173, whereby they both move pivotally in unison relative to post 174.

Pivot block 177 has a pair of spaced apart arms 178, each of which are engaged by corresponding recesses 179 in the sides of actuator block 181 mounted threadedly on the top of control rod 23. The top of control rod 23 has a slot 182 which permits rotation thereof by means of a screw driver or the like in order to adjust the requisite height of actuator block 181 relative to said rod. Threadedly mounted on the top of control rod 23 is a nut 183 for locking actuator block 181 into the desired location on said rod.

The reciprocating vertical motion of control rod 23 produces corresponding reciprocating motions on the part of pivot block 177, pivot bar 171, link bar 166, valve actuator 151, resulting in producing the reciprocating clockwise and counterclockwise motion of valve element 142 whereby negative pressure is induced alternately in chambers 18 and 19 of bell sections 11 and 12. It is to be noted that upon the action of valve element 142 to produce negative pressure in either one of chambers 18 or 19, the other chamber is exposed to the atmosphere through its respective port 137 or 136, while negative pressure is being applied through port 133 from the automotive manifold, or the like.

In some embodiments where the vacuum control valve is located centrally above wall 21 of bell section 11 to be actuated directly or axially by control rod 23, and where such a substituted valve control (not shown) does not

have any associated spring elements for producing snap action and for maintaining the valving element in its intermittent position between oscillations, it is contemplated that the apparatus of the present invention may be modified as shown in FIGS. 9 and 10 by providing within the interior of piston rod section 36 a helical, spiral spring 186, the larger end of which rests upon the floor 123 of the interior of said piston rod section while the upper, smaller portion of said spring extends freely upwardly into the interior of said rod section. Also mounted in the interior of piston rod section 36 is a helical coil spring 189, the upper end coil of which bears against and is retained frictionally within a recessed shoulder of tubular nut 43, the other end of said spring extending downwardly freely into the interior of said piston rod section.

Ring 122 within the interior of piston rod section 36 is normally spaced apart from either spring 189 or 186 when diaphragm 17 is at rest midway between bell sections 11 and 12. Ring 122 is capable of moving through approximately 60 to 80 percent of the length of the central portion of the interior of rod section 36 without contact with either of said springs when the latter are in their natural released conditions.

When diaphragm 17 is caused by negative pressure induced in chamber 19 to move downwardly, the lower end of spring 189 which is normally in the relaxed condition as shown in FIG. 10 impinges upon the top surface of ring 122 and becomes wholly or partially collapsed within the interior of nut 43. Thereafter, upon continued downward movement of diaphragm 17 and nut 43, ring 122 and control rod 23 also move downwardly until the point of dead center between alternate positions of the substituted vacuum control valve is reached, at which time spring 189 expands and produces an instantaneous overthrust force upon ring 122 to impel the latter to move beyond said dead center condition whereby said vacuum control valve is moved by rod 23 into a position which is alternate or opposite from the previous position of said valve.

Upon the change of position of the vacuum control valve, the pressure conditions on diaphragm 17 are changed in the opposite direction by the induction of negative pressure in chamber 18 thereby causing the diaphragm to move upwardly, during which time piston rod section 36 also moves upwardly. During this upward movement, floor 123 causes the upper free end of spring 186 to impinge upon the bottom surface of ring 122, whereby said spring 186 becomes collapsed between the bottom surface of ring 122 and floor 123. The continued upward movement of piston rod section 36 and floor 123 causes the concomitant upward movement of ring 122 and control rod 23. Here, again, when ring 122 reaches the location where the substituted vacuum control valve is at dead center, spring 186 expands and produces an instantaneous overthrust force upon ring 122 to urge the latter and control rod 23 beyond said dead center point whereby the vacuum control valve is moved into a position which is alternate or opposite from its previously held position in order to reverse the pressure conditions upon diaphragm 17.

The embodiment shown in FIGS. 9 and 10 is useful with an alternating vacuum control mechanism that is mounted centrally on the top of bell section 11 and substantially axial with control rod 23, where springs 186 and 189 perform the corresponding overthrust function as performed by spring 162 in the embodiment shown in FIGS. 2-8.

In both respective embodiments, spring 162 and springs 186 and 189 provide a snap action thrust for moving the respective vacuum control valves into opposite valving positions intermittently between oscillations from one position to the other. While a detent function is performed by spring 152 to maintain valve 142 in position between oscillations, other suitable detent means, known in the art, will be included in any substituted valve control element that would be mounted

axially with control rod 23 in the embodiment shown in FIGS. 9 and 10.

OPERATION

In operation, the apparatus is intended to act as a pump for producing air under pressure to supply power for apparatus such as windshield wipers, tire inflator mechanisms, shock absorbers, load leveling devices, air brakes, window locks, window openers and closers, seat adjusters, air horns, and the like, for automobiles and for other equipment such as air mattresses, water systems, paint, fertilizer and insecticide sprayers, and the like.

Being a vacuum operated pump, the apparatus is connected by way of coupling tube 132 to the manifold of an automotive engine or to other suitable sources of negative pressure. This negative pressure is controlled by way of an oscillating vacuum control valve to produce alternating negative pressure in chambers 18 and 19 within bell sections 11 and 12 containing a movable diaphragm 17 to which the pumping pistons are operatively connected. When negative pressure is induced through port 136 into chamber 19, said negative pressure causes diaphragm 17 to move downwardly as shown in FIG 1A. This action is permitted by exposing chamber 18 to the atmosphere through port 137 as shown in FIG. 2.

Toward the end of the downward motion of diaphragm 17 as well as of the downward motion of control rod 23, the linkages connected to the upper end of said control rod cause valve element 142 to move counterclockwise into the position shown in FIG. 3 where port 136, as well as chamber 19, are now exposed to the atmosphere and concurrently port 137 of chamber 18 is now connected to exhaust port 133 whereby negative pressure starts to be induced within chamber 18.

Because of the changed pressure conditions existing on diaphragm 17, the negative pressure in chamber 18 causes said diaphragm to move upwardly as shown in FIG. 1B.

Toward the end of the upward stroke of control rod 23, the linkages connected to the upper end of said rod now cause valve element 142 to move clockwise into the position shown in FIG. 2. By this action, port 137 and chamber 18 are now exposed to the atmosphere while port 136 and chamber 19 are now connected by way of exhaust port 133 to the continuing negative pressure being induced through tube 132. Thus, the alternating vacuum or negative pressure conditions are induced on opposite sides of diaphragm 17 to produce its oscillating action.

The oscillating motion of diaphragm 17 produces the concomitant oscillating motions of pistons 66 and 91. Upon the downward motion of piston 66, atmospheric air which enters the piston housing through apertures 104 pass through apertures 74 and apertures 72 into low pressure piston chamber 67 above piston 66. Upon the upward motion of piston 66, O-ring 49 seals off partition 28 while the air being compressed within chamber 67 passes through aperture 121 in piston section 36 into axial aperture 82 of piston section 81 and proceeds downward past valve 84 into high pressure piston chamber 92 below piston 91 which has moved into the upper position as shown in FIG. 1B.

Thereafter, when diaphragm 17 moves downwardly, pistons 66 and 91 also move downwardly during which time valve 84 becomes seated against valve seat 86 under the action of spring 87. The downward thrust of piston 91 further compresses the air in piston chamber 92 to a pressure that is higher than that which existed in piston chamber 67. The high pressure air from piston chamber 92 is urged by the action of the downward movement of piston 91 to open normally closed relief valve 112 against the action of spring 114 whereby the high pressure air is transmitted through outlet pipe 118 to work apparatus described hereinbefore.

In FIGS. 1A and 1B, the positions of pistons 66 and 91 are at rest at the ends of their respective strokes and O-rings 69 and 94 are not performing any sealing function in those positions.

In FIGS. 1C and 1E, said pistons have moved upwardly approximately 10% of their respective upstrokes from their positions shown in FIG. 1A. By virtue of increasing pressure in chamber 67 as a result of the upward movement of piston 66, O-ring 69 is urged downwardly against flange 73 to provide a seal between piston 66 and the interior wall of chamber 67. At the same time, O-rings 69 and 94 are not performing any sealing function of the increasing pressure within chamber 67 to provide a seal between chamber 67 and vacuum chamber 19 whereby all of the air being compressed in chamber 67 passes through aperture 121 in piston rod section 36 and thence into axial aperture 82 of piston rod section 81 thereby causing the opening of valve 84 against the action of spring 87 whereby air under pressure is introduced into high pressure chamber 92.

As the compressed air enters into chamber 92 during the upward movement of piston 91, air pressure in chamber 92 urges O-ring 94 upwardly against annular recess wall 98 (FIG. 1E) in order to seal off piston chamber 92 from atmospheric air pressure that exists above piston 91.

Notwithstanding the friction effect between O-ring 94 moving upwardly along the inner surface of chamber 92, nevertheless the increasing air pressure within chamber 92 will cause said O-ring to be urged upwardly against annular wall 98 of recess 93. Thus, the friction effect is offset by the increasing pressure obtaining in chamber 92.

FIGS. 1D and 1F represent the respective positions of pistons 66 and 91 after about 10% of their down strokes from their respective locations in FIG. 1B. As piston 66 moves downwardly, O-ring 69 is urged upwardly against flange 75 by friction with the interior wall of chamber 67 whereby atmospheric air that has entered into chamber 67 through ports 104 passes through ports 74 and ports 72 of piston 66 into the area of chamber 67 above piston 66, said air bypassing O-ring 69 as it moves upwardly through ports 72. During the downward motion of pistons 66 and 91, when negative pressure is being induced in chamber 19, said negative pressure is effective in urging O-ring 49 upwardly notwithstanding the downward movement of piston rod 36, thereby providing an effective seal between vacuum chamber 19 and chamber 67 above piston 66. Accordingly, no vacuum leak occurs that would reduce the efficiency of the negative pressure action taking place in chamber 19.

During the downward movement of piston 91 as shown in FIG. 1F, the increasing pressure within chamber 92 below piston 91 causes O-ring 94 to be urged upwardly against annular recess surface 98 to provide an effective seal for the increasing pressure being induced in high pressure chamber 92.

Except for the time during the instantaneous reversal of motion of diaphragm 17 and of pistons 66 and 91, O-ring 49 performs its sealing function during both the upward and downward movements of piston rod section 36. O-ring 49 is normally located within recess 47 with only slight peripheral squeeze being exerted against said O-ring when the apparatus is at rest. Said O-ring 49 is actuated to perform its sealing function during the downward motion of the pump components as shown in FIG. 1A by the induction of negative pressure within vacuum chamber 19 in bell section 12 in order to seal off partition wall 28 and to prevent any appreciable vacuum leak therethrough. The force of the negative pressure being induced in chamber 19 is greater than any frictional force that may be applied by the periphery of rod section 36 against O-ring 49 that would otherwise move the latter away from its annular seat. During the upward movement 70 of the pump components as shown in FIG. 1B, the up-

ward movement of piston 66 produces an increasing pressure in chamber 67 above said piston whereby said pressure causes O-ring 49 to be urged upwardly against its annular seat to perform its sealing function whereby the compressed air within chamber 67 above piston 66 may be transmitted through axial aperture 82 into the high pressure cylinder chamber 92. Thus, O-ring 49 is caused to produce its sealing function between partition wall 28 and piston rod section 36 during both rectilinear motions of said piston rod.

Notwithstanding the fact that control rod 23 extends from the interior to the exterior of the apparatus housing through top wall 21 to perform its function of operating the vacuum control mechanism, O-ring 26 operates to preserve the integrity of the negative pressure being induced in vacuum chamber 18 without any appreciable vacuum leak as has been experienced in prior art devices. While negative pressure is being induced in vacuum chamber 18 and rod 23 moves upwardly during at least a portion of that time, said negative pressure has sufficient force to urge O-ring 26 downwardly against its annular seat, overcoming any upward frictional force being exerted by the periphery of said rod against said O-ring, thereby producing a vacuum seal between rod 23 and the top wall 21 of bell section 11. During the downward movement of rod 23 while negative pressure is being induced in vacuum chamber 19, chamber 18 is exposed during that time to atmospheric air whereby it is unnecessary to provide any seal between rod 23 and top wall 21 of bell section 11. Also, the axial mounting of rod 23 obviates the necessity that existed in prior art mounting of control elements that involved the provision of bearings adjacent an aperture in a vacuum chamber wall thereby entailing considerable leakage of negative pressure both when the apparatus was performing its pumping function and when it was at rest.

The per stroke capacity of the compound piston compressor of the present invention is determined by the capacity within low pressure chamber 67 whose volume is usually between about two to five times that of high pressure chamber 92, or more. Substantially all of the air that is within chamber 67 above piston 66 is pumped into the high pressure chamber 92, regardless of any and all trapped air therein, and said air is all pumped out from chamber 92 except for some residual high pressure air remaining in chamber 92 since piston 91 does not reach the bottom of chamber 92 at the end of its downward stroke. The residual high pressure air remaining in chamber 92 below piston 91 at the end of its pressure stroke maintains O-ring 94 urged upwardly in a sealing position against recess wall 98 until pressure created by the up-stroke of piston 66 and transmitted into chamber 92 takes over and continues to maintain said O-ring in said sealing position.

According to performance tests of the compound piston compressor described herein, it has been found that the apparatus herein requires appreciably less volume of negative pressure to oscillate diaphragm 17 and appreciably fewer piston strokes to produce an amount of air pressure equal to that produced by other prior art compressors. Also, considerably less time is consumed in supplying or producing a given amount of compressed air than other prior art types of compressors.

A salient feature of the invention is the novel arrangement for mounting control rod 23 centrally and axially of diaphragm 17 and of pistons 66 and 91, and of piston rod sections 36 and 81. By virtue of this axial mounting, the natural longitudinal reciprocating thrusts of all of the moving parts within the interior of bell sections 11 and 12, and cylinders 59 and 61, is preserved without distortion and without producing any skewing action on said moving parts so that the latter can perform their pumping function with high efficiency. This is in contrast to prior art devices where alternating vacuum control mechanisms have been operated within the interior of the pump housing and located off center from the axis of the mov-

ing parts whereby pumping efficiency was diminished and alignment of the operating parts was skewed and subjected to unbalanced stresses. According to the present invention, the location of the control rod in the axial position produces no unbalancing stresses upon the interior working parts of the pump.

The balanced and undeviating axial reciprocating action of the operating parts of the pump is preserved with the axial location of control rod 23 whether the latter is operative through linkages to work alternating vacuum control valves located off center of the apparatus as shown in FIGS. 1-8, or when operating alternating vacuum control mechanisms mounted axially and aligned with said control rod on top of the apparatus as described in conjunction with FIGS. 9 and 10.

In prior art devices where actuating mechanisms were mounted off center upon pumping components in the interior pump housing, this produced off center stresses which resulted in the requirements of as much as twice the power to operate alternating vacuum control mechanisms. Such waste in power is eliminated by the mounting of control rod 23 axially of the operating parts in the present apparatus.

Although the present invention has been described with reference to particular embodiments and examples, it will be apparent to those skilled in the art that variations and modifications can be substituted therefor without departing from the principles and true spirit of the invention.

I claim:

1. A vacuum operated air compressor or pump comprising a housing, a pumping assembly located in the interior of said housing, a vacuum operated diaphragm connected to said pumping assembly in the interior of said housing, a vacuum control valve located on the exterior of said housing for producing alternating movement of said diaphragm and a movable control member connected to said valve, said control member extending through said housing and aligned axially in respect to said diaphragm and of said pumping assembly and operated by said diaphragm to produce alternating movements of said valve, said pumping assembly comprising a low pressure piston and a high pressure piston mounted axially in respect of each other, both of said pistons being located on one side only of said diaphragm in said housing, said low pressure piston performing its pressure stroke only in one direction of movement of said diaphragm and said high pressure piston performing its pressure stroke only in the opposite direction of movement of said diaphragm.

2. Apparatus according to claim 1 wherein said pumping assembly is located on one side only of said diaphragm and wherein said valve is movable alternately into two opposite control positions, and further comprising a pair of biasing means operative in opposite directions between said diaphragm and said control member for providing overthrust upon said control member to move said valve by snap action beyond the dead center position between its two opposite control positions.

3. Apparatus according to claim 2 wherein said pair of biasing means is located in the interior of said housing.

4. Apparatus according to claim 2 wherein lost motion is provided between the action of said diaphragm and said control member in both directions prior to the interaction therebetween for producing the respective longitudinal motions of said control member.

5. Apparatus according to claim 1 and further comprising a seal member between said control member and said housing, said seal member being activated by the induction of negative pressure in said housing adjacent said seal during the outward movement of said control member relative to said housing.

6. Apparatus according to claim 1 and further comprising a rod connecting said diaphragm to said pumping assembly, an axial aperture in said rod, a portion of said control member being movable longitudinally through

said aperture, spaced means in said rod within said aperture alternately engaging said control member in opposite directions of movement of said diaphragm to produce oscillating movements of said control member.

7. Apparatus according to claim 6 wherein lost motion relative to said control member is provided between the alternate engagements of said spaced means with said control member.

8. Apparatus according to claim 6 and further comprising a spring element adjacent each of said spaced means, said spring elements being operative upon said control member in respective opposite directions to provide overthrust for the movement of said control member after the latter is engaged by each of said spaced means.

9. A vacuum operated air compressor or pump comprising a housing, a vacuum chamber in said housing, a vacuum operated diaphragm within said vacuum chamber, a pumping chamber in said housing on one side only of said vacuum chamber, a partition between said vacuum chamber and said pumping chamber, and sealing means between said vacuum chamber and said pumping chamber, a double-acting pumping assembly operating within said pumping chamber, said pumping assembly being connected to said diaphragm through said partition and said sealing means, said double-acting pumping assembly performing a compression action during both opposite movements of said diaphragm.

10. Apparatus according to claim 9 wherein said double-acting pumping assembly comprises first and second pistons aligned adjacently end to end and axially in respect of each other, a first piston chamber in which said first piston operates, a second piston chamber in which said second piston operates, and means for transmitting air compressed by said first piston in said first chamber into said second chamber for further compression by said second piston.

11. Apparatus according to claim 10 wherein the capacity of said first chamber is in the range of about two to ten times the capacity of said second chamber.

12. Apparatus according to claim 9 wherein said sealing means is actuated during the movement of said diaphragm and of said pumping assembly in one direction by the negative pressure being induced in said vacuum chamber on one side of said partition and is actuated during the movement of said diaphragm and of said pumping assembly in the opposite direction by the positive pressure produced by said pumping assembly as it moves toward said partition.

13. Apparatus according to claim 12 wherein said sealing means comprises an O-ring in said partition, said O-ring performing its sealing function in one direction only during both movements in opposite directions of said diaphragm and of said pumping assembly in unison.

14. Apparatus according to claim 13 and further comprising a rod connected between said diaphragm and said pumping assembly, said rod moving through said partition and within said O-ring, said O-ring forming an effective seal between said rod and said partition during the rectilinear movements of said rod.

15. A vacuum operated air compressor or pump comprising a housing, a vacuum chamber in said housing, a vacuum operated diaphragm within said vacuum chamber, a pumping chamber in said housing on one side only of said vacuum chamber, a partition between said vacuum chamber and said pumping chamber, a double-acting pumping assembly operating within said pumping chamber, said pumping assembly being connected to said diaphragm through said partition, means for maintaining a seal in said partition between said vacuum chamber and said pumping chamber, a vacuum control valve located on the exterior of said housing for producing alternating movement of said diaphragm and a control member connected to said valve, said control member extending through the opposite side of said housing and arrayed

axially in respect of said diaphragm and of said pumping assembly, said control member, said diaphragm and said pumping assembly moving longitudinally and reciprocably in the same direction, said control member being operated by said diaphragm to produce alternating movements of said valve, said double-acting pumping assembly performing a compression action during both opposite movements thereof.

16. Apparatus according to claim 15 wherein said valve is movable alternately into two opposite control positions, and further comprising a pair of biasing means operative in opposite directions between said diaphragm and said control member for providing overthrust upon said control member to move said valve by snap action beyond the dead center position between its two opposite control positions.

17. Apparatus according to claim 16 wherein said pair of biasing means is located in the interior of said housing.

18. Apparatus according to claim 16 wherein lost motion is provided between the action of said diaphragm and said control member in both directions prior to the interaction therebetween for producing the respective longitudinal motions of said control member.

19. Apparatus according to claim 15 and further comprising a seal between said control member and said housing, said seal being activated by the induction of negative pressure in said housing adjacent said seal during the outward movement of said control member relative to said housing.

20. Apparatus according to claim 15 wherein said seal is actuated during the movement of said diaphragm and of said pumping assembly in one direction by the negative pressure being induced in said vacuum chamber on one side of said partition and is actuated during the movement of said diaphragm and of said pumping assembly in the opposite direction by the positive pressure produced by said pumping assembly as it moves toward said partition.

21. Apparatus according to claim 20 wherein said sealing means comprises an O-ring in said partition, said O-ring performing its sealing function in one direction during the movement in both opposite directions of said diaphragm and of said pumping assembly.

22. Apparatus according to claim 21 and further comprising a rod connected between said diaphragm and said pumping assembly, said rod moving through said partition and within said O-ring, said O-ring forming an effective seal between said rod and said partition during the rectilinear movements of said rod.

23. A pump comprising a housing, a bell section in said housing, a flexible diaphragm in said bell section dividing said section into two vacuum chambers, means for alternately inducing negative pressure successively in said vacuum chambers to cause said diaphragm to oscillate within said bell section, a first low pressure cylinder in said housing, a second high pressure cylinder in said housing, said first and second cylinders being aligned longitudinally in respect of each other on one side only of said bell section, sealing means isolating said bell section from said cylinders, a first low pressure piston movable longitudinally within said first cylinder, a second high pressure piston movable longitudinally within said second cylinder, a piston rod connected to said diaphragm, said first and second pistons being mounted on said rod

whereby said diaphragm and said two pistons move reciprocably longitudinally in unison, said first piston producing a compression stroke in one direction only, said second piston producing a compression stroke in the opposite direction only, and means for transmitting air compressed by said first piston in said first cylinder into said second cylinder.

24. A pump according to claim 23 and further comprising valve means located externally on said housing for alternately inducing negative pressure in said two vacuum chambers, an axial aperture in said piston rod,

a control element extending through said bell section and movable longitudinally within said axial aperture, said control element being connected to said valve means, means on said control element within said axial aperture and means in said piston rod within said axial aperture cooperating to produce oscillating movements on the part of said control element which, in turn, produces reversing movements on the part of said valve means for alternating the pressure conditions in the respective vacuum chambers.

25. A pump comprising a housing, a bell section in said housing, a flexible diaphragm mounted in said bell section and dividing the interior thereof into first and second vacuum chambers, means for subjecting said first and second vacuum chambers alternately to negative pressure and to atmospheric pressure for moving said diaphragm reciprocably within said bell section, a first cylinder in said housing, a second cylinder in said housing, said first and second cylinders being aligned longitudinally in respect of each other on one side only of said bell section, a partition between said bell section and said first cylinder, a piston rod connected to said diaphragm, said rod extending through said partition and into said first and second cylinders, sealing means mounted between said rod and said partition isolating said bell section from said first cylinder, said sealing means being activated in one direction of the rod movement by pressure produced in said first cylinder and being activated in the reverse direction of the rod movement by negative pressure being induced in the first vacuum chamber adjacent said partition.

26. A pump according to claim 25 and further comprising a first piston mounted on said piston rod and operative within said first cylinder, a second piston mounted on said piston rod and operative within said second cylinder, and means in said piston rod for transmitting air compressed by said first piston within said first cylinder into said second cylinder.

27. A pump according to claim 26 wherein said first cylinder has a larger diameter than said second cylinder.

28. A pump according to claim 25 and further comprising valve means located externally on said housing for alternately inducing negative pressure in said two vacuum chambers, a control element within said bell section and extending externally thereof, the external portion of said control element being connected to said valve means, said control element being operated by said diaphragm to produce oscillating movements on the part of said valve means for alternating the pressure conditions in said respective vacuum chambers.

29. A pump according to claim 28 and further comprising an axial aperture in said piston rod, a portion of said control element within said bell section extending into said aperture and movable freely longitudinally therein, means on said control element and means within said aperture cooperating only near the respective ends of the reciprocating motions of said diaphragm to cause said control element to operate said valve means.

30. A pump according to claim 29 and further comprising a first biasing element at the top of said aperture and a second biasing element at the bottom of said aperture, said first and second biasing elements cooperating with said control element to provide an overthrust for said control element during an intermediate portion of its movements in opposite directions.

31. A pump according to claim 28 and further comprising a sealing element between said control element and said bell section, said sealing element effectively preserving the negative pressure being induced in said second vacuum chamber.

32. A pump comprising a housing, a bell section in said housing, a flexible diaphragm mounted in said bell section and dividing the interior thereof into first and second vacuum chambers, means for subjecting said first and second vacuum chambers alternately to negative pressure and to atmospheric pressure for moving said diaphragm reciprocably within said bell section, a first low pressure cylinder in said housing, a second high pressure cylinder in said housing, said first and second cylinders being aligned longitudinally in respect of each other on one side only of said bell section, said low pressure cylinder having a greater diameter than said high pressure cylinder, a partition between said low pressure cylinder and said first vacuum chamber, a piston rod connected to said diaphragm, an aperture in said partition through which said rod moves reciprocably, said rod extending into said low pressure cylinder and said high pressure cylinder, a low pressure piston mounted on said rod and moving reciprocably within said low pressure cylinder, a high pressure piston mounted on said rod and movable reciprocably within said high pressure cylinder, sealing means mounted between said rod and said partition effectively isolating said first vacuum chamber from said low pressure cylinder, said sealing means being activated by pressure produced by the compression stroke of said low pressure piston, said sealing means being activated during the reverse stroke of said low pressure piston by negative pressure being induced in said first vacuum chamber, and means for transmitting air compressed within said low pressure piston into said high pressure cylinder.

33. A vacuum operated air compressor or pump comprising a housing, a vacuum chamber in said housing, a vacuum operated diaphragm mounted for reciprocating action within said vacuum chamber, a pumping chamber in said housing on one side only of said vacuum chamber, a sealed partition between said vacuum chamber and said pumping chamber, a double-acting pumping assembly in said pumping chamber and connected to said diaphragm through said partition, said pumping assembly moving reciprocably within said pumping chamber whereby the movement of said assembly in each opposite direction thereof constitutes a half cycle of operation of said pump, said pumping assembly performing a compression action during each half cycle of reciprocating movement thereof.

34. Apparatus according to claim 33 wherein said pumping assembly comprises first and second axially aligned adjacent pistons, a first cylinder within which said first piston operates, a second cylinder within which said second piston operates, the air compressed by the pressure stroke of said first piston during one half cycle of pump operation being urged into said second cylinder where it is further compressed by the pressure stroke of said second piston during the other half cycle of pump operation.
